DESIGN FOR A DENTAL SHADE GUIDE

Harry J. Russell, Toronto, Ontario, Canada, assignor to Baker & Company, Inc., Newark, N. J., a corporation of New Jersey

Application October 9, 1936, Serial No. 65,213

Term of patent 14 years

To all whom it may concern:

Be it known that I, Harry J. Russell, a subject of the King of Great Britain and a resident of Toronto, Ontario, Canada, have invented a new, original, and ornamental Design for Dental Shade Guide, of which the following is a specification, reference being had to the accompanying drawing, forming part thereof.

Figure 1 is a plan view of a shade guide showing my new design, and

Figure 2 is a side elevational view thereof.

The design essentially consists of a circular

thin disc-like center portion having a plurality of flat paddle-shaped arms radially disposed with respect to the center portion and projecting from the periphery of the latter intermediate opposite sides of the center portion, the radial arms having shank portions and relatively wider portions at their outer extremities. The radial arms of the guide are of different colors.

I claim:

The ornamental design for a dental shade guide as shown and described.

HARRY J. RUSSELL.
